(57) **CLAIM**

The ornamental design for a shopping cart, as shown and described.

DESCRIPTION

FIG. 1 is a first perspective view of a shopping cart.

FIG. 2 is a second perspective view of the shopping cart.

FIG. 3 is a front view of the shopping cart.

FIG. 4 is a rear view of the shopping cart.

FIG. 5 is a first side view of the shopping cart.

FIG. 6 is a second side view of the shopping cart.

FIG. 7 is a top-down view of the shopping cart; and,

FIG. 8 is a bottom-up view of the shopping cart.

The broken lines shown in the drawings depict portions of the shopping cart that form no part of the claimed design.

1 Claim, 8 Drawing Sheets
